UNITED STATES PATENT OFFICE.

WALTER JOSEPH WODRASKA, OF NEW YORK, N. Y.

PLAYER-PIANO ACTION.

1,349,481.

Specification of Letters Patent. Patented Aug. 10, 1920.

Application filed May 2, 1919. Serial No. 294,234.

To all whom it may concern:

Be it known that I, WALTER J. WODRASKA, a citizen of the United States, and a resident of the city of New York, borough of Manhattan, in the county and State of New York, have invented a new and Improved Player-Piano Action, of which the following is a full, clear, and exact description.

This invention relates to automatic or self playing musical instruments and has particular reference to player piano actions. By the term "piano," however, I do not wish to be unnecessarily limited in the following specification and claims to any specific type of instrument, it being understood that certain features of my improvement relating especially to the pneumatic control may be applicable as well to automatic organ actions or the like.

Among the objects of the invention is to provide a player piano action of the most compact and simple construction adapting it for cheap manufacture, easy and inexpensive assemblage, and convenience of access for inspection, repair or interchange of parts.

Another object of the invention is to provide for each pneumatic or pair of vertically aligned pneumatics a single and detachable valve block, the same providing for easy inspection or repair of any valve or associated parts without disturbing any of the other valve mechanisms.

A further object is to provide improved valves so balanced as to be most responsive to the pneumatic operation.

A still further object is to improve the hammer operating means with respect especially to the bell crank rocker arm for each pneumatic and certain devices coöperating with said rocker.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical transverse section of a portion of a piano illustrating my im-

provement, the plane of the section being indicated at the line 1—1 of Fig. 2.

Fig. 2 is a front elevation of the mechanism at the lower portion of Fig. 1, parts being broken away at different planes.

Fig. 3 is a horizontal sectional detail on the broken line 3—3 of Fig. 1.

Fig. 4 is a vertical sectional detail on the broken line 4—4 of Fig. 1.

Fig. 5 is a rear elevation of the diaphragm devices with parts in section on the line 5—5 of Fig. 1.

Fig. 6 is a rear elevation of the valve block as would be seen from the plane of the line 6—6 of Fig. 1; and

Fig. 7 is a view corresponding to a portion of Fig. 1 and indicating the changed position of the movable parts of the pneumatic action.

Referring now more specifically to the drawings I show a self-playing musical instrument including a tracker board 10 over which the note sheet 11 operates in any well known or approved manner, and from which a series of tubes 12 lead to a corresponding number of individual vacuum pockets 13 in the upper portion of the valve casing indicated as a whole at 14. This casing is provided at one end or at any other desired points with an air trunk 15 from which a tube 16 leads to any suitable pump or suction appliances, not shown, for the purpose of maintaining a suitable vacuum in a vacuum chest 17 extending along the entire casing.

The valve casing 14 includes an upright support or base panel 18 along the rear and open surface of which are formed air channels or grooves 19 each leading throughout the length of the panel and providing free inlet for atmospheric air through inlet ports 20 bored directly horizontally through the panel 18. Adjacent to each inlet port 20 is formed an exhaust port 21 shown in the drawings as being directly above the inlet port and communicating at its inner end with a passage 22 in which is located a normally open inlet valve 23 and whereby a condition of atmospheric air normally obtains throughout the inlet port 20, passage 22, exhaust port 21, and the interior of the pneumatic 24 associated with these features. For the sake of compactness and simplicity of construction as well as facility for in-

spection and repair I provide the pneumatics in pairs, one pneumatic of each pair being above the other and with their vertical stationary backs 25 fixed to the grooved surface 5 of the panel 18 over the grooves 19. The movable backs 26 of the pneumatics are arranged substantially vertically but one in a direction opposite to the other, or as indicated with the ends thereof having maximum throw adjacent to each other and opposite the middle portion of the valve casing so that links 27 pivotally connected to the movable backs 26 may connect with the upper ends or arms 28 of bell crank rockers 29 10 15 20 25 30 pivoted at 30 upon bearings 31, one for each rocker, and secured upon a base rail 32 along the rear portion of the casing 14. Thus the points of connection 28 between the links 27 and the rockers are all coaxial and the rockers are all identical with one another.

The rest rail 33 lies beneath and normally supports the rearwardly extending arm 34 of each rocker which is slotted horizontally at 35 to afford maximum flexibility of action in its coöperation with the adjustable tappet 36 carried by the hammer, jack or abstract 37. Each rocker has longer and shorter arms, the longer arm being linked to the pneumatic while the shorter arm is 30 arranged to directly attack the abstract 37 constituting a part of the striking mechanism. A check rail 38 is fixed in spaced relation to and above the arms 34 and carries a series of adjustable tappets 39 for easy 35 and individual regulation of the throw of each of the rockers. The parts are maintained in the relative positions indicated in Fig. 1 either by gravity or suitably arranged springs, and so each pneumatic is normally 40 distended and filled with atmospheric air.

The vacuum chest 17 is provided or constituted by the space between the panel 18 at the rear and a diaphragm panel 40 in front. These panels are connected by strips 45 41 and 42 at the top and bottom respectively rigidly connected in any suitable manner to the upper and lower edges of the base panel 18, while the diaphragm panel 40 is removably connected to the strips 41 and 42 50 55 60 by screws 43, or their equivalent. The vacuum chest 17 thus formed is largely filled by means of the valve blocks 44 already referred to, but sufficient space is left to insure free communication along the vacuum chest for the exhaust of the air and pneumatic action dependent thereon. The diaphragm panel 40 is a unitary structure coextensive in length with the valve casing 14 and is provided with a diaphragm 45 60 65 for each valve, each diaphragm having its margin glued or otherwise secured upon the rear surface of the panel 40 while the main portion of the diaphragm is loosely and flexibly held for normal projection forward into a cavity 46 shown best in Fig. 2 as

elliptical in form with its major axis upright. To the rear face of the central portion of the diaphragm is fitted a contact strip or reinforcement 47 against which the front head 48 of the valve bears. From each of the cavities 46 leads a port 49 shown as extending upward into communication with the individual vacuum pocket 13 at the top of the valve casing 14. A pin hole 50 affords communication between the port 49 and the vacuum chest 17 in order to establish an equilibrium of pressures on opposite sides of the diaphragm except as such equilibrium is disturbed during the operation of the device. 70 75 80

Each valve block 44 accommodates two valves, one above the other as shown. Each valve considered as a whole comprises a stem 51 to the rear end of which is fixed the inlet valve 23, already referred to, and to the front end of which is fixed the head 48, while intermediate of the inlet valve and head is fixed what may be termed a vacuum valve 52. While the inlet valve 23 is adapted to coöperate with but is normally spaced from the front end portion of the inlet port 20 as a valve seat, the vacuum valve 52 is normally closed being seated forward against a valve seat 53 in the nature of a metal plate or the like fixed as by screws 54 to the front surface of the block 44. While the inlet valve 23 is located and operates within the passageway 22 formed in the rear wall of the block, the vacuum valve is similarly fitted in a pocket 55 formed in the front wall of the block. The passage 22 and pocket 55 have free communication with each other through an opening 56 arranged between the top of the pocket 55 and the central portion of the passage 22 and hence 100 105 110 115 120 above the axis of the stem 51. Said stem has loose sliding bearing in a hole 57 bored through the block just below and parallel to the hole 56. In this connection I wish to note that the valve as a whole is practically balanced between the inlet and vacuum valves by virtue of the character of the support for the valve so that the valve as a whole is maintained with its stem practically horizontal at all times and so is free to reciprocate as intended for the opening and closing of the respective valves carried thereby. By this arrangement I am able to provide a valve mechanism of relatively short reciprocation but maximum reliability of action 125 because of the manner of constructing and balancing the valves for direct coöperation in alternation with their respective seats.

From the foregoing specific description of the mechanism its mode of operation may be briefly summarized as follows: Assuming the parts in the position shown in Fig. 1 with the condition of atmospheric air in the pneumatics and all other parts and cavities at the right side of the vacuum valves 52 130

and with a condition of suitable vacuum in the vacuum chest 17, cavities 46, ports 49, and pockets 13, if the note sheet 11 be operated so as to bring a perforation in register 5 with the upper end of a tube 12 atmospheric air will be admitted downward through the tube 12, pocket 13, port 49 and cavity 46, giving the diaphragm so affected a rearward puff causing the unseating of the 10 vacuum valve 52 and the seating of the inlet valve 23. The unseating of the vacuum valve, by reason of the area of the diaphragm being greater than that of the valve, establishes communication between the 15 vacuum chest and the hole 56 and thus the pneumatic immediately collapses due to the air pressure upon the rear wall 26 thereof while the air from within the pneumatic passes freely into the vacuum chest. The 20 closing of the valve 23 causes the momentary shutting off of communication between the inlet port 20 and the passage 22 so that the intended action of the pneumatic is not interfered with by the open grooves 19. When 25 the perforation through the note sheet will have passed the hole in the tracker board the vacuum condition is reestablished in the cavity 46, and the vacuum valve 52 will be promptly seated thereafter into normal position permitting the free inlet of air 30 through the inlet port 20, passage 22, and port 21 into the interior of the pneumatic. Thus it will be seen that my improved pneumatic action in and relating to the valve 35 casing 14 is of the most compact and simple construction not only occupying a minimum amount of space, but affording maximum facility for inspection, repairs, or the like.

I claim:

40 1. In a pneumatic player piano, the combination of a valve casing, a plurality of pneumatics carried thereby, hammer actuating means coöperating with the pneumatics, said casing being provided with a vacuum chest common to a plurality of the pneumatics, a series of valve blocks arranged within the vacuum chest, a plurality of independent valves supported by and within each block 45 and controlling communication between the

atmospheric air in the respective pneumatic 50 and the vacuum in the chest, and means to provide pneumatic actuation of each valve.

2. In a valve chest for pneumatic player pianos, the combination of a plurality of walls affording a vacuum chest coextensive 55 with the valve chest, a plurality of individual valve blocks fixed to one of the walls and within the vacuum chest, a reciprocating double valve structure in each of the blocks and supported between its valves in 60 said block for reciprocation to control communication between the atmosphere and vacuum chest, and means providing for the pneumatic actuation of each valve so supported.

65

3. The herein described pneumatic player piano action comprising a valve casing having formed therein a vacuum chest, a series of independent valve blocks secured in the chest, each block carrying a plurality of valve mechanisms, each valve mechanism comprising a stem, an inlet valve at one end of the stem, a head at the other end of the stem and a vacuum valve intermediate of the inlet valve and head, said valves being 75 adapted to seat on their respective seats in alternation, the valve stem being supported for reciprocation in a hole formed through the valve block, and a diaphragm device for actuating the valve through contact with 80 said head.

4. In a player piano, the combination with a pair of pneumatics arranged one above the other in direct vertical alinement and having their active ends adjacent to 85 each other, a pair of rockers pivoted coaxially of each other back of the pneumatics, and means connecting the individual pneumatics with the alined upper ends of the rockers, of a check rail extending longitudinally along and spaced from said rockers, individually adjustable stop means carried by the check rail for coöperation with the individual rockers, abstract means, and means to cause the rockers to attack the abstract means but disconnected therefrom.
